COMBINED MICROPHONE HOLDER WITH INTEGRAL CORD STORAGE THEREFOR

Samuel F. Swayze, Rochester, N.Y., assignor to Eastman
Kodak Company, Rochester, N.Y.

Filed June 4, 1973, Ser. No. 366,400

Term of patent 14 years

Int. Cl. D14— 03, 99
U.S. Cl. D26—14 J

FIG. 1 is a top front perspective view of a combined microphone holder with integral cord storage therefor; and

FIG. 2 is a bottom rear perspective view thereof.

I claim:

The ornamental design for a combined microphone holder with integral cord storage therefor, as shown.
